(57) **CLAIM**

The ornamental design for a welding device enclosure, as shown and described.

DESCRIPTION

FIG. 1 is a front perspective view of the welding device enclosure showing our new design;

FIG. 2 is a rear perspective view of the welding device enclosure of FIG. 1;

FIG. 3 is a front view of the welding device enclosure of FIG. 1;

FIG. 4 is a rear view of the welding device enclosure of FIG. 1;

FIG. 5 is a right side view of the welding device enclosure of FIG. 1;

FIG. 6 is a left side view of the welding device enclosure of FIG. 1;

FIG. 7 is a top view of the welding device enclosure of FIG. 1; and,

FIG. 8 is a bottom view of the welding device enclosure of FIG. 1.

The broken lines show portions of a welding device enclosure that form no part of the claimed design.
